HYDRAULIC PRESS

Richard W. Dinzl, Narberth, Pa., assignor to
 Baldwin-Southwark Corporation, a corpora-
 tion of Delaware

Application November 9, 1935, Serial No. 49,050

1 Claim. (Cl. 60—52)

This invention relates generally to hydraulic presses and more particularly to an improved control system therefor. It is an object of my invention to provide an improved control system for a hydraulic press whereby a positive variable displacement uni-directional discharge pump may be effectively and efficiently employed to supply operating fluid alternatively to a main operating cylinder or to pull-back cylinders. A further object is to provide improved control means for the pump to insure gradual acceleration and deceleration of the press movements.

Another object is to provide improved means for preventing the movable platen from falling in the event that power for the pump motor should fail. A still further object is to provide an improved control system adapted to accomplish all of the foregoing objects, as well as others, in a manner which is simple and economical in construction, operation and maintenance insofar as is permissible with the character of subject matter herein disclosed.

Other objects and advantages will be more apparent to those skilled in the art from the following description of the accompanying drawing in which:

Fig. 1 is a diagrammatic outline of my improved control system applied to a hydraulic press;

Fig. 2 is a modified arrangement of a solenoid control arranged to cooperate with my improved control system to hold the press up in the event of power failure;

Figs. 3 and 4 are modified arrangements for adjusting the pump stroke in accordance with platen movement.

In the particular embodiments of the invention, such as are disclosed herein merely for the purpose of illustrating certain specific forms among possible others that the invention might take in practice, I have diagrammatically shown a hydraulic press having a lower stationary platen 1 and an upper movable platen 2 actuated by a ram 3 in a main cylinder 4. Pull-back rams and cylinders 5 may be arranged in any suitable manner for returning platen 2 to its upper position. A usual filling tank 6 is adapted to have free communication with main cylinder 4 upon opening of a filling valve 7 which is normally urged to its closed position by a spring whereby filling liquid under relatively small air pressure may open the valve during initial down movement of ram 3. A pilot ram and cylinder 8 is adapted to be supplied with fluid pressure to

open the filling valve during return movement of the platen.

To initiate down movement of the press, a manually operable pivoted lever 10 is pressed down against the action of a spring 11 and held by a pivoted latch 12 as shown in Fig. 1. A control rod 13 is thereby moved down with lever 10 to shift a four-way manual control valve, generally indicated at 14, to the right shown in Fig. 1. Thereupon fluid from a variable positive displacement pump 15 having uni-directional discharge, preferably of the Hele-Shaw type as disclosed in Patent No. 1,250,170, to Hele-Shaw et al., is supplied through a discharge pipe 16, check valve 17 and a pipe 18 to main cylinder 4. Also fluid is drawn from pull-back cylinders 5 through a pipe 20, valve 14 and pump suction pipe 21 to the inlet of pump 15. Exhaust of draw-back fluid permits platen 2 and ram 3 to lower by gravity during which time filling fluid from tank 6 opens filling valve 7 to admit low pressure fluid to the main cylinder. When the platen engages the work, pump pressure builds up in the main cylinder and accordingly closes the filling valve thereby to continue the pressing stroke.

The main cylinder pressure is transmitted through a pipe 22 and upon reaching a predetermined value raises a plunger 23 normally urged downwardly by a suitable adjustable spring. Raising of plunger 23 releases latch 12, whereupon spring 11 rotates hand lever 10 in a counterclockwise direction to cause rod 13 to shift valve 14 to the left and accordingly connect pump discharge pipe 16 to pipe 20 for raising the press through the pull-back rams. Simultaneously main cylinder 4 is connected to pump exhaust pipe 21. Pump pressure is transmitted through a pipe 24 to pilot cylinder 8 for opening filling valve 7 when pump pressure builds up in pipe 20, thereby permitting free flow of a large volume of low pressure liquid from cylinder 4 to the filling tank 6. Inasmuch as the pump and its stroke control are well known devices, detailed description thereof is not deemed necessary.

A particularly desirable improvement of my present invention resides in the following described pump control for gradually stopping the platen when it returns to a predetermined top position as well as effecting a gradually accelerated down movement of the press. This gradual deceleration and acceleration are accomplished by employing a spring 27 for normally biasing the pump to its full stroke position and then controlling a usual pump stroke ad-

justing stem 28 in accordance with platen movement through an operative connection therewith. This connection may be by a bellcrank 29 suitably connected through any necessary links or levers to a rod 30 upon which an adjustable position stop collar 31 is secured for engagement with any suitable platen abutment 32. With this arrangement it is seen that as the platen moves upwardly, it will engage stop 31 and cause pump control rod 28 to move to the right against the action of spring 27, thereby gradually reducing the pump stroke until the pump is returned substantially to its neutral position, at which time the press will stop in its upper position. The press will remain on a sufficiently short stroke to maintain pressure in the pull-back cylinders for holding up the press. Hence any tendency of the platen to creep or drift downwardly will immediately permit link 30 to move downwardly 15 and accordingly increase the pump stroke so as to supply sufficient fluid to the drawback cylinders for restoring the platen to its upper position. The foregoing operation of stopping the platen in its upper position is accomplished without any adjustment of hand lever 10 after its latch 12 is released by the action of pressure responsive plunger 23.

It will be seen that the foregoing pump stroke control also has the advantage that when hand lever 10 is initially pressed down to shift valve 14 and thereby start the press down, then the pump by already being on short stroke will cause fluid to be gradually withdrawn from the drawback cylinders and thereby permit only a gradual 30 initial down movement. However, the platen movement will be gradually accelerated due to stop 30 and link 31 moving down with the platen and thus permitting spring 27 to gradually increase the pump stroke to its full position.

Another arrangement for controlling the pump stroke is to provide, as shown in Fig. 3, the upper end of rod 30 with a cam 35 which will therefore move vertically in accordance with platen movement and engage the outer end of pump control rod 28 to adjust it as in Fig. 1. As shown in Fig. 4, the accelerating and decelerating functions may be performed and also variable rates of platen movement at any portion of its stroke may be accomplished by employing a suitably shaped cam 36 oscillated or otherwise moved in synchronism with the platen 2 through any suitable connections to rod 30. Stroke control rod 28 may suitably engage the cam.

In the event of power failure for the pump motor, there is a tendency for the weight of the ram and platen 2 to force oil from the pull-back cylinders through pipe 26 and valve 14 and thus run pump 15 backward, thereby permitting the press platen to fall, it being understood that control valve 14 is in its left hand position while the press is up thus causing pipes 16 and 26 to be in communication with each other. However, reverse flow through pipe 26 from the pull-back cylinders is prevented by check valve 17 thereby automatically holding up the press in the event of power failure.

If it is desired to perform a die setting operation, the operator would move control valve 14 in either direction merely by manually raising and lowering hand lever 10 without permitting latch 12 to hold the lever down. The check valve 17 will not interfere with this die setting operation because the pump would always be discharging in one direction through pipe 16.

Fig. 2 illustrates a modified arrangement for

preventing the press from dropping in the event of power failure. This means comprises an air operated servo-motor 38 whose piston is secured to the stem of control valve 14 and is normally urged in a left direction by a suitable spring. A valve 39 is normally closed by energization of a solenoid 40 connected to a pump motor circuit whereby upon failure of the motor power, solenoid 40 is deenergized to open valve 39 and admit air pressure from any suitable source 40a through 10 a pipe 41 to operate air motor 38 and thus shift control valve 14 only to its neutral position in which the valve is shown in Fig. 2. Fluid pressure would be thus locked in the drawback cylinders and accordingly insure that the press will be 15 held up. When the power is restored, solenoid 40 will be energized to exhaust air pressure from motor 38 through pipe 40b. Valve 14 can thereupon, if desired, be manually shifted to the left, from its neutral position shown in Fig. 2, for 20 effecting a press stroke. By utilizing the solenoid control, it is possible to directly control the pump stroke for a die setting operation through any suitable link and lever arrangement connected to bellcrank 29, one such connection being diagrammatically indicated in its simplest form by a handle 42 directly connected to bellcrank 29, Fig. 2. It is assumed in the use of hand lever 42 that the pump is adapted to have some degree of reversibility as by shifting the pump on negative stroke 30 such as is possible with the Hele-Shaw type of pump. This reversible feature would only be used in connection with the use of the direct die setting control lever such as 42 and even then it is necessary that control valve 14 should be in its 35 left end position so as to connect pipes 16 and 20 with the pull-back cylinders. Hence it is seen that by moving the pump stroke in one direction or the other from neutral by lever 42, fluid pressure can be alternatively supplied either to the 40 pull-back cylinders to raise the platen or discharged therefrom to permit the platen to lower. In this operation, check valve 17 is omitted, but nevertheless the press is prevented from falling in the event of power failure by reason of solenoid 45 control 40 and air motor 38 which will return valve 14 to its neutral position and thus lock pressure in the pull-back cylinders instantly upon power failure.

From the foregoing disclosure it is seen that 50 I have provided means that is particularly effective for automatically controlling press operations such as automatic reversal and stopping of the press at any predetermined top position, as well as effecting gradual acceleration in the initial 55 down movement of the platen and gradual deceleration thereof as it approaches its upper position, the gradual acceleration and deceleration being specifically accomplished in an extremely simple manner by short stroking a uni-directional 60 displacement pump through a direct mechanical connection with the press platen. This particular arrangement in combination with the manually operable reversing valve which permits a uni-directional displacement pump to be used for 65 effecting both up and down movements of the press provides an extremely effective and simple control system while the automatic power control means insures complete safety to the workmen as well as avoiding possible damage to the dies. 70

It will of course be understood that various changes in details of construction and arrangement of parts may be made by those skilled in the art without departing from the spirit of the invention as set forth in the appended claim. 75

I claim:

In combination, a hydraulic press having a platen operated by a main ram and cylinder and a pull-back ram and cylinder, a power driven variable stroke positive displacement pump, a control valve adapted to distribute fluid from said pump alternatively to said cylinders to effect pressing and reversing operations, means for au-

tomatically effecting and maintaining short stroking of said pump in accordance with movements of the platen when in its returned position thereby to hold up the platen, and solenoid controlled means for returning said control valve to its neutral position automatically upon failure of pump pressure.

RICHARD W. DINZL.
